UNITED STATES PATENT OFFICE

JAMES JOSEPH ROWBOTTOM, OF CHICAGO, ILLINOIS

DESIGN FOR A COMBINED SMOKER'S STAND LAMP

Application filed April 13, 1931. Serial No. 39,468. Term of patent 3½ years.

To all whom it may concern:

Be it known that I, JAMES J. ROWBOTTOM, a citizen of the United States, residing at Chicago, in the county of Cook and State of Illinois, have invented a new, original, and ornamental Design for a Combined Smoker's Stand Lamp, of which the following is a specification, reference being had to the accompanying drawing, forming part thereof.

The figure is a view in perspective of a combined smoker's stand lamp, showing my new design.

I claim:

The ornamental design for a combined smoker's stand lamp, as shown.

JAMES JOSEPH ROWBOTTOM.
